UNITED STATES PATENT OFFICE.

ONOFRE LINDSAY AND OSCAR HIDALGO, OF VALPARAISO, CHILE.

STAMP.

1,220,863.

Specification of Letters Patent.

Patented Mar. 27, 1917.

Application filed April 12, 1916. Serial No. 90,641.

To all whom it may concern:

Be it known that we, ONOFRE LINDSAY and OSCAR HIDALGO, citizens of the Republic of Chile, residing at Valparaiso, Chile, 5 5 South America, have invented certain new and useful Improvements in Stamps; and we do hereby declare the following to be a full, clear, and exact description of the invention, such as will enable others skilled 10 in the art to which it appertains to make and use the same.

This invention relates to hand stamps and more particularly to a stamp embodying an ink pad, holder and means for securing a 15 wax or other type of stencil sheet over the ink pad.

The invention has for its primary object to provide simple and effective means for attaching the ink pad or absorbent sheet 20 to the holder including a spring presser plate having a chamber designed to contain ink and perforations in the plate to permit the ink to flow over the ink pad.

With these and other objects in view, the 25 invention consists in the novel construction, combination and arrangement of parts as will be hereinafter specifically described, claimed and illustrated in the accompanying drawing, in which:

30 Figure 1 represents an end elevation of the stamp,

Fig. 2 represents a side elevation of the presser plate removed,

Fig. 3 represents a fragmental perspective view of one end of the presser plate and handle connected therewith, and

Fig. 4 represents a perspective view of the ink pad or absorbent sheet removed.

Referring to the drawing in detail, where- 40 in similar reference numerals designate cor- responding parts throughout the several views, the numeral 5 indicates a rigid body plate constructed of sheet metal or other material, in the center of which is secured 45 a knob or handle 6. The longitudinal edges of the plate 5 are turned inwardly under the plate and are curved downwardly to provide a pair of guides or retaining mem- bers 8. A presser plate, designated gen- 50 erally by the numeral 9 is arranged below the body plate 5, and the longitudinal edge portions 10 thereof are curved upwardly and removably engaged between the extreme

longitudinal edges 11 and inwardly directed portions 7 of the edges of the body plate 5. 55 The extreme edges of the spring presser plate 9 are turned over a substantially U-shaped wire 12, constituting a handle whereby the presser plate may be removed longitudinally from the body plate 5. 60

The end or transverse edges of the presser plate 9 are turned upwardly to provide end walls 13, which are connected with the upwardly turned sides 10 of the presser plate to provide an ink containing chamber 14. 65 The portion of the presser plate intermediate the end walls 13 of the upwardly curved sides 10 is formed with a plurality of relatively small perforations 15, to permit the ink contained within the chamber 14 to flow upon the inner surface of the ink pad or absorbent sheet 16, and also to permit the ink held in the pad by capillary attraction to flow into the chamber 14 when the pad is compressed. 70

The longitudinal edges of the pad 16 are bound by metallic strips 17 carrying hooks 18 adapted to engage in slots 19 formed in the upwardly curved sides 10 of the spring presser plate 9, whereby the pad is secured 80 in position under the presser plate. 75

The stamp is particularly designed for use in connection with a wax or other type of stencil sheet 20, which is secured in position over the spring presser plate 9 and 85 over the ink pad by engaging the longitudinally curved edges thereof between the upwardly curved edges 10 of the presser plate and the inwardly directed portions 7 of the body plate. 90

What we claim is:

1. A stamp including a body plate having two of the opposed edges curved, a handle carried by said body plate, a spring pressed plate spaced from said body plate and having upwardly curved edge portions engaged with the curved edges of said body plate, end walls carried by said spring presser plate and connected with the upwardly curved edge portions of the presser plate 100 to form an ink receptacle, said presser plate having a plurality of perforations therein, and an ink pad secured to said spring presser plate and adapted to receive ink from said receptacle. 105

2. A stamp including a body plate, a

spring presser plate removably secured in spaced relation to said body plate and having an ink containing chamber, said presser plate having a plurality of perforations in the lower portion thereof, and an ink pad arranged under said presser plate and removably secured to the latter.

In testimony whereof we affix our signatures in presence of two witnesses.

ONOFRE LINDSAY.
OSCAR HIDALGO.
